(57) **CLAIM**

The ornamental design for a caster wheel lock bracket, as shown and described.

DESCRIPTION

FIG. 1 is a top perspective view of a caster wheel lock bracket showing our new design;

FIG. 2 is another top perspective view thereof;

FIG. 3 is a top plan view thereof;

FIG. 4 is a bottom plan view thereof;

FIG. 5 is a rear elevational view thereof;

FIG. 6 is a left side elevational view thereof, the right side being a mirror image; and,

FIG. 7 is a front elevational view thereof.

The broken lines shown in FIGS. 1–7 immediately adjacent the shaded areas represent the bounds of the claimed design, and all other broken lines are for illustrative purposes only. None of the broken lines form a part of our claimed design.
